UNITED STATES PATENT OFFICE.

WILHELM ANDERSSON, OF PEARSON, WASHINGTON.

SELF-SOAPING WASHBOARD.

Application filed September 19, 1922. Serial No. 589,173.

To all whom it may concern:

Be it known that WILHELM ANDERSSON, a citizen of Finland, residing at Pearson, in the county of Kitsap and State of Washington, has invented new and useful Improvements in Self-Soaping Washboards, of which the following is a specification.

The object of the invention is to provide a soap holding and feeding attachment for wash boards whereby the operative or exposed surface of a cake of soap may be held at all times in a fixed relation to the plane of the rubbing surface of the board regardless of the gradual wearing away of the soap due to the use thereof in the washing operations, and in this connection to provide a soap holding means adapted to form a permanent part of a wash board into which a bar of soap may readily be introduced and which when in place is protected except at its forward surface which is located substantially in the plane of the rubbing surface of the board; and with these objects in view the invention consists in a construction and combination of parts of which a preferred embodiment is shown in the accompanying drawings, wherein:—

Figure 1 is a view of a wash board having a soap holding means constructed in accordance with the invention and arranged at the top of the rubbing surface of the board.

Figure 2 is a vertical sectional view of the same.

Figure 3 is a transverse section taken on the plane indicated by the line 3—3 of Figure 1 or longitudinally of the soap holder.

Figure 4 is a rear view of a portion of the board.

Figure 5 is a view of a wash board showing the soap holder arranged at one side of the rubbing surface.

The soap holding means which may be used in connection with a wash board of any well known or conventional type such as that illustrated at 10 in the drawing consists essentially of a rearwardly open frame 11 set into and secured to the frame of the wash board and having parallel sides 11^a and pins 11^b to define a soap seat in which operates a follower plate or board 12 sup-

ported and actuated by a leaf spring 13 which is preferably hingedly mounted at 14 upon the wash board frame or other fixed object adjacent to the end of the soap seat and is spanned by soap rods 17 forming a 55 grating against which the front surface of the bar of soap indicated at 18 bears so that with the exception of the practically engageable portion of the soap surface covered by said rods the entire area thereof is exposed 60 for contact with fabrics rubbed thereover in the operation of moving them across the rubbing surface of the board, to take up the necessary amount of the soap for cleansing purposes. 65

The renewal or replacement of the soap or introduction of a fresh bar thereof may be effected by releasing the free end of the follower carrying an actuating spring and swinging said follower out of the soap seat, 70 and when the follower is replaced it is obvious that the tendency thereof under the tension of the actuating spring is to force and hold the bar snugly in contact with the stop rods so that as it wears away in use the surface of the bar is maintained substantially 75 in the plane of the rubbing surface of the board and as the follower is of an area approximating that of the soap receiving seat the practically complete and economical use 80 of the bar of soap may be effected.

In the modified construction or arrangement indicated in Figure 5 the soap holding and feeding means having substantially the same features as above described is disposed 85 with its length parallel with that of the wash board, and therefore in order to avoid obstruction to the fabrics in rubbing them over the exposed surface of the soap bar the stop rods 17^a are disposed longitudinally of the seat instead of transversely as in the form of the device illustrated in Figure 1, and a portion of the rubbing surface of the board is cut away for the exposure of the soap bar. 95

Having described the invention, what is claimed as new and useful is:—

A wash board having an open soap seat adapted for the reception of soap in bar form and spanned at its front side substan- 100

tially in the plane of the rubbing plane of the board by stop rods for limiting the forward movement of a soap bar, a follower fitted in the soap seat for contact with a contained soap bar, and a follower actuating and carrying spring hingedly mounted for supporting the follower in contact with the

rear side of a soap bar mounted in the seat, means being provided for securing the free end of said spring in its operative position. 10

In testimony whereof he affixes his signature.

WILHELM ANDERSSON.
